UNITED STATES PATENT OFFICE.

ALEXANDER SAMUELSON, OF TERRE HAUTE, INDIANA, ASSIGNOR TO ROOT GLASS COMPANY, OF TERRE HAUTE, INDIANA.

DESIGN FOR A BOTTLE OR SIMILAR ARTICLE.

48,160.

Specification for Design.

Patented Nov. 16, 1915.

Application filed August 18, 1915. Serial No. 48,196. Term of patent 14 years.

To all whom it may concern:

Be it known that I, ALEXANDER SAMUELSON, a citizen of the United States, residing at Terre Haute, in the county of Vigo and State of Indiana, have invented a new, original, and ornamental Design for Bottles or Similar Articles, of which the following is a specification, reference being had to the accompanying drawings, forming a part thereof.

I claim:

The ornamental design for a bottle or similar article, as shown.

ALEXANDER SAMUELSON.

Copies of this patent may be obtained for five cents each, by addressing the "Commissioner of Patents, Washington, D. C."
